EDGE TRIMMER GRINDER

Ernest Dunford, St. Louis, Mo., assignor to Landis Machine Company, St. Louis, Mo., a corporation of Missouri

Application September 9, 1937, Serial No. 162,967

11 Claims. (Cl. 51—225)

This invention relates to the art of grinding rotary cutters of which one example is the cutter used for trimming the edges of shoe soles and having a series of deeply recessed and peculiarly shaped teeth. It is to be understood that the use of the invention is not limited to cutters of this specific class but such a cutter and the grinding wheel therefor and elements of the mounting for the cutter are illustrated in the associated drawing.

The main object of the invention is to facilitate the application of a cutter tooth to the grinding wheel and a quick removal of the cutter from the grinding wheel and the ready rotation of the cutter on its mounting to present another tooth to the wheel.

Another object of the invention is to insure the accurate spacing of the ground surfaces of successive teeth irrespective of the skill of the operator and irrespective of the number of times that the cutter has been ground or the extent to which the original cutting surfaces have been worn down.

Another object of the invention is to readily accommodate different diameters of cutters and variations in the thickness and diameter of the grinding wheel.

These general objectives and other more detailed objectives as will be apparent from this specification, are attained by the structure illustrated in the accompanying drawing, in which:

Figure 1 is, in part, a front elevation of the end portion only of a shoe trimmer with a cutter grinding wheel and cutter mounting fixture applied thereto, the portion of the fixture being sectioned to more clearly illustrate its construction;

Figure 2 is an end elevation of the structure shown in Figure 1; and

Figure 3 is a top view of so much of the structure as necessary to illustrate certain features described.

Figure 4 is a similar view showing the parts in another position.

The end of the trimmer frame, indicated at 1, journals a rotating shaft 2, projecting beyond the frame and carrying a grinding wheel 3. The cutter to be sharpened on the wheel is indicated at 4 and is of a familiar contour, embodying a series of radial teeth 5, with their cutting edges 6 facing circumferentially of the wheel.

The fixture which mounts the cutter comprises a bracket 7, the base 8 of which fits against the end of the trimmer frame 1 and is secured in place by screws 9. A stud 10 has its left hand end threaded into a boss 11 on bracket 7 and the right

hand end of stud 10 forms a pivot 12 for a cutter support arm 13, which can oscillate about the stud axis. A handle 19 on arm 13 facilitates the pivotal movement of arm 13 about stud 10.

A knurled sleeve 15 secured to stud 10 enables the user to rotate the stud and thereby shift pivot 12 towards and away from the bracket base or transversely of the plane of the grinding wheel 3. Screw 16, threaded through boss 11 may be tightened to engage stud 10 and hold it against the movement just described.

A cap 14 attached to the end of pivot 12 retains support arm 13. A spring 26 compressed between a shoulder on stud 10 and arm 13 thrusts the latter to the right. There is a slight clearance indicated at C (Figure 1) between arm 13 and the edge of sleeve 15, permitting a slight movement of arm 13 to the left for the purpose hereinafter mentioned.

The upper end of arm 13 terminates in a vertically disposed spindle 17, journalling cutter 4, there being a flange 18 at the base of the spindle for supporting the cutter.

An upstanding finger 22 is pivoted on arm 13 and a coil spring 23 tends to move finger 22 toward the common axis of spindle 17 and cutter 4. During such movement the upper end of finger 22 enters the space between two successive teeth 5 (Figure 3). The right hand face x of finger 22 is disposed at such an angle that it substantially coincides with the engaged cutting face of the tooth 5a. The opposite face y of finger 22 is beveled or rounded so that as the finger moves inwardly toward the cutter axis it engages tooth 5b and holds the cutter against play about its spindle, irrespective of variations in the space between teeth 5a and 5b as may result from repeated grinding.

A lug 20 on finger 22 is positioned to strike a pin 21 on bracket 7 to arrest the movement of arm 13 away from the grinding wheel (Figure 4), but after elements 20 and 21 are engaged, heavier pressure on handle 19 will stretch spring 23 and the arm may be moved farther away from the wheel, finger 22 remaining stationary, clearing the cutter so that the latter may be rotated on spindle 17 to present a new tooth to the finger and to the wheel. Movement of the arm inwardly towards the grinding wheel is positively limited by the engagement of a lug 24 with a stop screw 25 adjustably mounted in a lug 27 on the lower portion of the bracket (Figure 2).

With the parts in position as indicated in Figure 1, the tooth face opposing the grinding wheel will be spaced slightly therefrom but upon manual

movement of arm 13 to the left to the extent provided by clearance C, the tooth face will be brought against the wheel, as indicated in Figure 3. When the surface of the tooth has been 5 ground to the extent permitted by the contact of finger 22 with the next tooth, pressure on arm 13 is released, the tooth and wheel separating under the thrust of spring 26. The operator then rotates arm 13 on pivot 12 until the parts are in the 10 position shown in Figure 4, whereupon the cutter wheel may be rotated one tooth and the positioning and grinding operation repeated.

The construction described results in the uniform application of successive cutter teeth to the 15 grinding wheel, irrespective of the operator's skill, for the reason that finger 22 and spring 23 hold the cutter against movement about the spindle axis, and stop elements 24 and 25 limit movement of the cutter inwardly toward the wheel. 20 Assuming that the cutter teeth are evenly spaced in the original article, it will follow that the successive grindings will be equal on all teeth due to the positioning of the tooth being ground by the engagement of finger 22 with the next tooth 25 and, assuming that the operator will grind all of the teeth on the cutter and not remove the cutter with only a few of the teeth ground. Even in the event of such an improper grinding operation, if the cutter is again placed on the fixture 30 and the grinding operation performed throughout a complete rotation of the cutter on spindle 17, the cutting surfaces will be evenly spaced from each other as in the original cutter. If the cutter is very dull and the first application of teeth to 35 the wheel does not produce keen edges, the repeated application will result in further removal of metal from the tooth face and this cycle may be repeated.

When the grinding wheel wears down, set screw 40 16 may be loosened and stud 10 adjusted to the left to bring the cutter mounting block closer to the wheel grinding face. With such adjustment, finger 22 is also moved bodily and the cutting face of the tooth will be maintained parallel to the 45 grinding face of the wheel.

Obviously, details of the structure may be changed substantially from those illustrated and described above without departing from the spirit of the invention and the exclusive use of such 50 modifications as come within the scope of the claims is contemplated.

I claim:

1. In combination, a grinding wheel, a support arm pivoted about an axis substantially parallel 55 to and substantially spaced from the axis of said wheel, said arm having a cutter journaling spindle adjacent to said wheel with its axis extending transversely of said wheel axis, a finger pivoted on said arm about an axis extending transversely of 60 the axis of said spindle, said finger terminating adjacent to said spindle and having an element tapered to enter the recess between two cutter teeth so that its opposite sides engage a cutter tooth cutting face and an opposing face of an adjacent tooth, and a tension spring connecting said 65 arm and finger and thrusting said finger inwardly of said recess to effect such engagement.

2. In combination, a grinding wheel, a bracket, a support movable thereon substantially parallel 70 to the plane of the grinding surface of said wheel and including a spindle for journaling a circular cutter so that it may rotate in a plane transversely of said first mentioned plane, a part movable on said support into position to engage a 75 cutter tooth, a stop on said bracket engaging said

part and limiting its movement with said support, said support being movable with said cutter after said stop and part engage to free said cutter from said part.

3. In a device of the class described, a grinding 5 wheel, a fixture for mounting a cutter to be applied to said wheel and comprising a fixed bracket, a stud mounted on said bracket, and the axes of said stud and wheel being substantially parallel, means for securing said stud at various points 10 transversely of the plane of said wheel, an arm having a cutter journaling spindle and oscillating on said stud to move said spindle towards and away from said wheel, and means for engaging the cutting face of a cutter to position the cutter 15 and to hold the same positively against rotation on said spindle during the grinding operation.

4. A device as described in claim 3 in which the cutter holding means moves with the arm for a portion of the movement of the latter, the device 20 including stops which then hold said means against movement with said arm so that said arm and a cutter thereon may clear said means and accommodate rotation of said cutter to present another tooth to the grinding wheel. 25

5. In a grinding fixture of the class described, an oscillating support for a circular cutter, spaced devices for limiting the oscillating movement of said support, a member movable to different positions on said support to engage the cutter or to 30 release the same, said member moving with said support to hold said cutter to properly present a tooth to the grinding wheel and said member co-operating with one of said devices to be held against movement with said support to free the 35 cutter from said member and permit the rotation of the cutter on said support to present another tooth to said wheel.

6. In combination, a grinding wheel, a stationary pivot, a support arm mounted on said pivot, 40 whereby said arm may swing towards and away from the axis of said wheel, there being a cutter journaling spindle on said arm with its axis extending transversely of said wheel axis whereby a cutter rotated thereon may present successive 45 teeth to the grinding face of said wheel, means on said arm for holding a cutter against rotation on said spindle, said arm having sliding movement on said pivot to bring a tooth face against said wheel. 50

7. A device as described in claim 6 which also includes means yieldingly thrusting the arm along its pivot away from the grinding face of the wheel.

8. In combination, a grinding wheel, a stationary pivot, a support arm mounted on said pivot 55 whereby said arm may swing towards and away from the axis of said wheel, there being a cutter journaling spindle on said arm with its axis extending transversely of said wheel axis whereby a cutter rotated thereon may present successive 60 teeth to the grinding face of said wheel, means on said arm for engaging a cutter tooth other than the tooth being ground to hold the cutter against rotation on said spindle, said arm having sliding movement on said pivot to bring a tooth 65 face against said wheel.

9. A device as described in claim 8 which also includes means yieldingly thrusting the arm along its pivot away from the grinding face of the wheel.

10. In a device of the class described, a grinding wheel, a stud with its axis disposed substantially parallel to the axis of said grinding wheel, a portion of said stud comprising a pivot, an arm mounted on said pivot and adapted to support a cutter in position to have its teeth presented to 75

said wheel, said arm being rotatable on said pivotments to move a cutter towards and away from the periphery of said wheel and said arm being slideable on said pivot to move the face of a cutter tooth towards and away from the grinding face of said wheel, there being opposing elements on said arm and stud limiting the sliding movement of said arm, there being means on said arm for holding said cutter in position thereon, said ele-

5
extents of grinding which can be effected on a cutter tooth at a single presentation of a tooth to said grinding wheel.

11. A device as described in claim 10 which also includes means yieldingly thrusting the cutter supporting arm away from the grinding wheel. 5

ERNEST DUNFORD.
